199,671

FURNITURE BASE

George C. Mulhauser, Jr., 545 Clinton Road,
Paramus, N.J.

Filed May 15, 1962, Ser. No. 70,148

Term of patent 14 years

(Cl. D15—1)

FIG. 1

FIG. 2

FIGURE 1 is a side elevational view of the furniture base of the present invention.

FIGURE 2 is a top or plan view thereof.

The faces of the base not shown in FIGURE 1 are substantially plain.

I claim:

The ornamental design for furniture base, as shown and described.

References Cited by the Examiner

UNITED STATES PATENTS

2,135,586 11/38 Lorenz et al.

OTHER REFERENCES

Interiors, December 1958, page 120, top center, view 2, chair by J. G. Furn. Co.
Restaurant Equipment Dealer, September 1961, page 47, right side, item 7984, pedestal base.

EDWIN H. HUNTER, Primary Examiner.

JOEL STEARMAN, Examiner.